Specification of Letters Patent.

Patented July 3, 1917.

Continuation of application Serial No. 876,272, filed December 9, 1914. This application filed September 9, 1915. Serial No. 49,762.

To all whom it may concern:

Be it known that I, FREDERICK D. SCHNEIDER, a citizen of the United States, residing at Cleveland, in the city of Lakewood, county of Cuyahoga, and State of Ohio, have invented a new and useful Improvement in Heaters, of which the following is a specification, the principle of the invention being herein explained, and the best mode in 10 which I have contemplated applying that principle, so as to distinguish it from other inventions.

This invention has general reference to heater constructions and more particularly to two distinct features incident to its structural arrangement and mode of operation. Heretofore two types of heater have been employed for the purpose of heating the water supply required for domestic usage. 15 One consisted of a heater of small capacity which heated the water contained within a comparatively large storage tank. While this type gave service it was wasteful and extravagant due to radiation lost in keeping 20 a large tank hot. The other utilized a heating conduit of capacity meant to be large enough to sufficiently heat the flow from a faucet under normal pressure, and the burners of which were automatically lighted from a 25 pilot flame when the gas valve was opened by the water pressure. At times this type was too large and frequently too small when 30 an inordinate supply was required. Conditions under one extreme made it wasteful and under the other extreme temporarily insufficient. As such my new type of water 35 heater combines both an automatic and an instantaneous operation with a storage supply. Specifically it involves a thermostatically 40 controlled automatic and instantaneous control of the inlet valve of a gas burner.

The construction makes a unit of a storage heater or of an automatic instantaneous heater together with a storage tank. Moreover, the invention as applied to such a unit 45 and employing a reversed circulation water conduit of substantially the arrangement but not necessarily the configuration shown counteracts the wasteful tendency of the water to continue to circulate upwardly just after the burner is out, by dropping into the hottest conduit portions and then rising therethrough. My heater construction effects

a sort of trap whereby the tendency of water to drop in both sections of the conduit 55 brings about a counteraction and causes a cessation in circulation. The arrangement of the cold water or inlet coils above furthermore wholly avoids condensation upon the lower hot water coils and consequently 60 the destructive action of sulfuric acid into which such condensation is converted, while practically all of the condensation on the upper cold water section is converted into steam and the remainder is shed by suitable 65 baffles.

One object has been to contrive a heater for domestic purposes which will constantly maintain a given amount of water at a fixed temperature, whereby water may be drawn 70 at such temperature:

(a) Sooner, owing to the larger flow and because the emptying of the heating conduit need not be first awaited.

(b) In larger quantity, that is, in excess 75 of the quantity it is capable of heating instantaneously.

(c) For a proportionately long period of time.

In short, the service of a storage heater 80 and the economy of an instantaneous heater is had. Heretofore it has not been possible to effect this triad of results with a single heater because the heating capabilities of so much of the water conduit as was disposed 85 within the casing (that is, the rapidity with which it could satisfactorily heat a standard flow) were insufficient relative to the capacity of the storage supply, and because the burner did not automatically render additional heat when some of the storage supply 90 was replaced by cold water.

An instantaneous automatic water heater constructed and arranged after the manner of my conception will heat the water as it 95 is used, but is not limited in capacity; will not cut the water pressure at any faucet since it functionates independently of water pressure being entirely without a water valve and since it usually does not require 100 a regulating cock; will be controlled solely by the temperature of the water and therefore not by the pressure thereof; will give standard service at any number of faucets at one time. My heater is not a storage system with a needlessly large storage which 105

is wasteful of heat, rather a combination of an automatic instantaneous heater to satisfy normal demand with a small storage to meet unusual or abnormal demands and 5 a sensitive snap thermostat to control the fuel and temperature when associated with an exterior pipe connection. By normal demand is meant the quantity of water that can be instantaneously and continuously 10 raised the standard of 63° in temperature. By abnormal demand is meant a varying quantity of heated water occasionally required for immediate delivery in excess of the normal demand. Normal demand can be 15 constantly supplied. Abnormal demand can be intermittently supplied.

A perfect fuel gas analysis in a heater would show no trace of either oxygen or carbon monoxide. This theoretical ideal has 20 however been unattainable. To avoid any trace of carbon monoxide would imply a perfect primary mixing of air and gas which is, however, impossible in practice. Therefore, complete combustion must be obtained 25 by supplying extra or secondary air at the mouth of the burner. The control of such secondary air within close limits has proven so difficult that some excess oxygen generally occurs when complete combustion is 30 had. An excess of oxygen tends to cool. The presence of carbon monoxide denotes a waste of gas. Of the two evils the former is the lesser. In consequence it is of considerable importance to study the control of 35 the needed supply of secondary air whereby to so apportion and direct it that a minimum quantity is permitted to enter the heater at definitely located points and still maintain a complete combustion. Owing to the total 40 absence of any condensation in my heater a drip pan may be dispensed with and the supply of secondary air properly conducted from below.

With the foregoing and other objects in view the invention consists of the novel construction, combination and arrangement of parts as hereinafter more specifically described and illustrated in the accompanying drawings, wherein is shown an embodiment 45 of the invention, but it is to be understood that changes, variation and modifications can be resorted to which come within the scope of the claims hereunto appended.

This application is a continuation of my 50 earlier copending case Serial Number 876,272, as to all matter common to the two applications.

Figure I is a side elevation of an exemplifying heater construction embodying my 55 invention.

Fig. II is an end view of Fig. I showing certain parts broken away.

Fig. III is a view corresponding to Fig. I with the front of the casing removed in 60 section to disclose the interior.

Fig. IV is a section of line IV—IV of Fig. III looking to the left as directed by the arrows.

Fig. V is a section on line V—V of Fig. I looking downwardly and showing the 70 burner partially broken away.

A casing designated entire with the reference character A comprises suitable legs a' which support a bottom having definitely sized and located openings a². Such bottom 75 supports near one end one or more burner seats a³ one of which is well shown in Fig. III. The relative dimension and arrangement of the secondary air openings a² is particularly shown in Fig. V. It will be 80 noticed that each is directly beneath a given burner head so that the rising air is caused to swirl around the same and actually mix rather than pass directly between two adjacent burner heads to constitute a cooling air 85 current above. In this manner a very large per cent. of the secondary air is efficiently utilized. The front wall a⁴ of the casing is provided in its lower part with a door a⁵ whereas the rear wall a⁶ of the casing 90 is provided with an opening near its top which is in connection with a stack a⁷. It will be noticed that the casing involves a double set of walls the inner one of which may be cast iron and the outer any suitable 95 insulating material. One of the ends, namely, the one at the left as appears in Fig. III is provided near its bottom with a number of openings a⁹, in this instance four, to correspond with the number of 100 burners employed in this particular exemplification. The openings a⁹ are disposed substantially on a level with the tops of the burner supports a³. Some distance higher up the end a⁸ of the casing is provided with 105 additional openings a¹⁰ which reference character should be assumed as applied to an opening in both walls as a unit. Actually there are six of these openings and their 110 purpose will hereinafter appear. The upper extremity of the end a⁸ is fashioned with an approximately semicircular recess a¹¹ of maximum dimensions. The opposite end a¹² of the casing is provided midway with a large opening a¹³ nearly corresponding in 115 height with the height of the door a⁵ though positioned somewhat higher up. This opening a¹³ should similarly be understood to extend through both walls of the end a¹² of the casing, as is again apparent in Fig. III. 120 The upper extremity of the end a¹² is provided with a recess a¹⁴ similar to the recess a¹¹. A door or perhaps more properly a removable panel a¹⁵ is adapted to close the opening a¹³ when affixed as by screws a¹⁶. 125 The upper and lower edges of the panel a¹⁵ are provided with six equally spaced grooves, those above being designated as a¹⁷ and the lower ones as a¹⁸. Each superposed pair of grooves a¹⁷ and a¹⁸ is disposed in 130

the same endwise plane as one of the openings a^{10} . These grooves are best seen in Fig. II, such parts as are broken away having been so shown for the very purpose of disclosing them.

5 Seated and suitably packed within the recesses a^{11} and a^{14} so as to effectually close the upper end of the casing A and be in turn partially enveloped thereby is an elongated storage tank B of smaller capacity than has heretofore been generally employed. One end of the tank, namely the left end, is provided with a conduit inlet b' . Above, a pipe b^3 will be presumed as leading to the faucet. The outlet b^2 communicates by means of a flange connection b^4 with a manifold b^5 provided below with an opening b^6 intended for the insertion of the sensitive tube of a snap-control thermostat embodying the invention of H. J. Long, filed September 14, 1914, Serial No. 861,511. While this manifold has six outlet openings corresponding with and spaced as the grooves a^{17} connections with only one will be described. Connected with the outlet of the manifold b^5 is the male part b^7 of the common type of union. The female part b^8 of this union is supported upon the upper inlet extremity b^9 of a zigzag interiorly positioned portion of the water conduit. This conduit is clearly shown in Fig. III to embody the well known principle of both a downward and an upward flow. According to my invention, however, the interiorly disposed portion or portions of the conduit with its alternately inclined interjacent sections is each substantially flat in its entirety so as to be capable of lying within a vertical plane as is well shown in Fig. IV. Such alternate 40 inclination involves above straight interjacent sections connected by return bends b^{11} through which the water travels downwardly, and next a directly downwardly extending portion b^{12} leading into a T b^{13} to which a drain cock b^{14} is connected. This cock projects outwardly through the groove a^{18} as is shown in Figs. II and III. Thereafter the travel of the water is upwardly through straight alternately inclined sections b^{15} and return bends b^{16} . The outlet extremity b^{17} passes through the opening a^{10} and carries the female part b^{18} of another union. The male part b^{19} of such union is likewise connected with one of the inlets of a manifold b^{20} which is in turn connected at b^{21} with a pipe b^{22} communicating with the inlet b' .

65 A series of baffle sheets constitute an important though not indispensable feature even of this exemplification of my invention. As here utilized they coact not only to compel a long zigzag travel of the gases of combustion ending by passage along the entire extent of the bottom of the storage tank to keep it heated, but also to shed such small

condensation as occasionally collects on the upper cold water portion of the conduit. These baffles may be seen in Figs. III and IV to extend from opposite ends of the heater casing and to be alternately inclined upwardly in opposite directions. The uppermost of such baffles b^{23} is carried solely by the casing just below the stack opening a^7 so as to be spaced a given distance from the other end. This particular baffle therefore compels the gaseous elements to pass along the bottom of the tank B. The other five baffles are all designated as b^{24} and rest upon different interjacent sections of the conduit, preferably as appears in the drawing. 80

It should now be manifest that owing in part to the configuration of so much of the water conduit as is disposed within the confines of the casing, and in part to the provision of the removable panel a^{15} any one 85 of the interior conduit units may be withdrawn through the opening a^{13} after disconnection from the manifolds b^5 and b^{20} . Thus a facility is occasioned of removing any section of the conduit which has developed 90 a flaw or for any other reason, and this may furthermore be accomplished independently or without disturbing in any wise the connection of any other conduit section.

95 A plurality and in this instance four burners C, have inlet ends c' extending through the openings a^9 and opposite extremities c^2 suitably mounted upon the supports a^3 . The burners C each carry a plurality of enlarged, laterally projecting and removable stools c^8 . Secured to the inlet ends c' outwardly of the end a^8 of the casing, is a mixing valve c^4 connected by a pipe length c^5 with a gas manifold c^6 leading, through the agency of a bent pipe connection c^7 , to a valve c^8 in connection with the source of fuel supply. The operation of the valve c^8 is controlled by means of the type of thermostat c^9 earlier referred to and which comprises a sensitive tube c^{10} adapted by means of a flexible connection c^{11} to actuate the valve stem c^{12} . In this manner a heater construction is provided which is instantaneous and automatic in its action and such automatic action is dependent upon the operation of a thermostat rather than through the agency of water pressure. This is believed to be new as applied to an instantaneous water heater, the new result attained being an arrangement whereby a 100 thermostat is enabled to turn on the gas as soon as water is drawn from the storage tank and which tank is of sufficiently small capacity as compared with the heating capacity of the interior water conduit and 105 burners in their relation to each other, that a storage supply of water is constantly maintained at a predetermined temperature with a minimum of waste by radiation of heat therefrom. 110

1 claim:

1. In apparatus for heating and causing the circulation of water, a casing, a conduit system therein which includes; a passage having a downward direction from its inlet to its discharge end, a second passage located below the first and having an upward direction from its inlet to its discharge end, a duct connecting the lower discharge end of the first mentioned passage with the lower inlet and of the second mentioned passage, and a storage tank connected with the upper inlet of said first mentioned passage and with the upper outlet of said second mentioned passage; a burner below said passages, a fuel valve for controlling the supply to said burner, and a thermostat operatively connected with said conduit and with said fuel valve, and adapted to control the latter in response to variations of temperature in the former, the arrangement being such that the coldest water is trapped in the lowermost part of said conduit upon each automatic cessation of heat from the burner.
2. An automatic instantaneous water heater construction comprising a casing, heating means in communication therewith, a water conduit above said heating means, a hot water storage tank carried directly by said casing and in connection with opposite ends of said conduit, said tank being adapted to absorb heat from said casing, and automatically operating means comprising a thermostat set in one of said connections for controlling said heating means, the full capacity of said tank being comparatively small with reference to the heating capacity of the conduit whereby a predetermined temperature of the entire supply of water in said tank may be economically maintained and a given measure of hot water may be immediately drawn from said tank without lighting said heating means.
3. A combination automatic storage and instantaneous water heater construction comprising a gas burner below, a valve for said burner, a conduit above said burner adapted to conduct a changing supply of water to be instantaneously heated to such degree and in such quantity as to satisfy normal demand, a hot water storage tank disposed above for fulfilling limited normal as well as abnormal demand, said tank being connected with said conduit and with a service faucet, a casing enveloping both conduit and tank whereby to reduce the radiation of heat from the latter, and a thermostat for operating said valve to one or the other of its extreme positions and adjusted and arranged to functionate automatically only after a predetermined minimum drop in temperature whereby a given amount of water may be drawn from the tank without flashing on said burner.
4. In an apparatus for heating and caus-
- ing the circulation of water, a closed endless conduit system which includes a zig-zag passage comprising elongated interjacent portions and having a continuously downward direction from its inlet to its discharge end, a second zig-zag passage comprising elongated interjacent portions located below the first and having a continuously upward direction from its inlet toward its outlet end, and a duct which connects the lower discharge end of the first mentioned passage and the lower intake end of the second mentioned passage, a gas burner located below said passages, a comparatively small elongated tank located above and connected with both of said passages, an elongated inclosing casing which embraces said passages tank and burner, and a thermostat controlled by the temperature of the water above both of said passages and operatively connected with said burner whereby a predetermined storage supply is maintained at a constant temperature both because such supply is at automatically regulated intervals in the path of the heat units and because in circulation with said heated passages.
5. A combination instantaneous and storage water heater construction comprising a casing, burner, a valve controlling the supply of fuel to said burner, a water conduit disposed within said casing and above said burner and pilot for continuously furnishing normal demand, a hot water storage tank carried above so as to intersect the path of travel of the heat units and connected with the inlet and outlet of said conduit and with a service faucet, said tank being of small capacity relative to the heating capabilities of said conduit for instantaneously furnishing a predetermined minimum as well as abnormal demand; and a thermostat operatively connected with the circulating system and actuated by the resultant change in temperature of the water therein either by radiation of a predetermined amount of heat or drawing of a predetermined amount of water therefrom, for operating said valve to one or the other of its extreme positions.
6. A gravity circulation water heater comprising a casing, a water conduit therein for delivering a given flow, a burner below adapted to raise the temperature of the water flow through said conduit to a predetermined standard degree, the effective relationship between the measure of water flow through said conduit and the heat given off by said burner being adapted to satisfy normal demand, a storage tank for periodically supplying abnormal demand located above and connected with said conduit, and a thermostatic device actuated by a predetermined degree of temperature in the circulatory system for controlling the heat from said burner, the value of the ratio between the amount of flow in gallons that can be so

raised per minute to standard temperature and the number of gallons representing the capacity of the tank varying between certain limits whereby improved service with 5 a saving of fuel is assured in the manner specified.

7. An automatic instantaneous and storage water heater comprising a casing, a water conduit therein for delivering a 10 given flow sufficient for normal domestic usage, a gas burner below said conduit to deliver heat units capable of raising by a given amount the initial temperature of the flow through said conduit whereby to 15 continuously fulfil normal demand, a storage tank located above and connected with said conduit, said tank being of relatively small capacity solely for supplying abnormal demand, the ratio between the number 20 of gallons representing the capacity of said tank and the number of thermal units absorbed by the water in the conduit to furnish normal demand being definitely established, a valve for said burner, and a thermostatic device for automatically operating 25 said valve in response to a change of predetermined range in the temperature of the water supply, whereby to simultaneously satisfy a limited abnormal demand from 30 said storage supply.

8. An automatic instantaneous and storage "water" heater unit of not less than three gallon normal (instantaneously heated) capacity, comprising a casing, a 35 gravity circulation water conduit therein having a capacity to deliver a given minimum flow, a gas burner below to deliver heat units capable of raising by a standard number of degrees the initial temperature of 40 the flow through said conduit with consideration of its size, whereby to meet normal demand, a storage tank carried directly by said casing connected with said conduit, said tank being of relatively small capacity 45 and purposed for supplying abnormal demand; with a range of variation in the

ratio between the number of gallons representing the capacity of said tank and the number of gallons emerging from said conduit per minute for furnishing normal demand being established between definite limits, a valve for said burner, and a snap-acting thermostatic device operatively connected near the bottom of said tank for automatically actuating said valve in response 50 to a predetermined change of temperature of the storage supply whereby the temperature of the water in both tank and conduit is determined by the automatic control of said burner solely by said thermostat.

9. In apparatus for heating and causing the circulation of water, a casing, a conduit system therein which includes; a zig-zag tube having a downward direction from its inlet to its discharge end, a second zig-zag tube located below the first and having an upward direction from its inlet to its discharge end, a duct connecting the lower discharge end of the first mentioned tube with the lower inlet end of the second mentioned tube, and a storage tank extending over the said zig-zag tubes and connected with the upper outlet of said second mentioned tube; baffles alternately projected from opposite ends and forming a zig-zag 65 flue passage, a burner below said tubes and in communication with said flue passage, a fuel valve for controlling the supply to said burner, and a thermostat operatively connected with said conduit and with said fuel 70 valve, and adapted to control the latter in response to variations of temperature in the former, the arrangement being such that condensation is shed from the upper and entirely avoided upon the lower of said 75 tubes during the repeated automatic ignition of said burner whereby to prolong the life of said tubes in the manner specified.

Signed by me, this 28th day of August, 1915.

FREDERICK D. SCHNEIDER.
